FUEL BURNER CONTROL SYSTEM

Ernest M. Miller, Excelsior, Minn., assignor to
 Minneapolis-Honeywell Regulator Company,
 Minneapolis, Minn., a corporation of Delaware

Application July 14, 1941, Serial No. 402,301

5 Claims. (Cl. 158—28)

The present invention is directed broadly to systems for automatically controlling fuel burners and is more particularly concerned with systems which have a timed trial ignition period and a device for detecting the presence or absence of combustion, and which are of the so-called "non-recycling" type on flame failure.

It is old in the prior art in connection with fluid fuel burners, such as oil burners, to provide an automatic control system in which a thermal safety switch times the trial ignition period. That is, on a call for heat by the thermostat in control of the system, the burner motor and ignition device as well as the heater for the safety switch are energized. If combustion is established within a predetermined time the safety switch heater is effectively deenergized and the burner motor remains energized, but if combustion is not established the safety switch is opened and the system is shut down.

It is an object of the present invention to provide a system, such as described in the preceding paragraph, which will reenergize the safety switch heater and shut the system down upon a flame failure following the successful establishment of combustion and not allow the burner motor to be re-energized without a manual operation. Ordinarily the safety switch would have the same timing upon a flame failure as upon an original failure to establish combustion (usually about 90 seconds) which means that following a flame failure and a reenergization of the safety switch heater by the combustion responsive switch, the burner motor would remain energized and would pump raw fuel into the combustion chamber of the furnace for 90 seconds. In order to eliminate this disadvantage I materially reduce the timing of the safety switch following a flame failure.

It is therefore a prime object of this invention to connect the heater for the thermal safety switch in series with an electrical impedance, such as a relay winding, upon an original call for heat and to connect it directly across the source of power to materially reduce the safety switch timing upon a flame failure following the successful establishment of combustion.

It is a further object, where a relay winding is used, to control an ignition device with the relay, thus providing an intermittent ignition system.

These and other objects will readily become apparent as the following specification is read in the light of the accompanying drawing, the single figure of which schematically illustrates

an oil burner control system embodying my invention.

Although my invention will be described in connection with an oil burner control system, it will readily be appreciated that it may be used in combination with control systems employing other types of fuel, and I therefore do not intend to be limited merely to the use of my invention with a system for controlling an oil burner.

Referring now to the drawing, the reference numeral 10 indicates generally the usual form of room thermostat which comprises a bimetallic element 11 fixed at one end and carrying at its free end a pair of resilient contact blades 12 and 13 which cooperate respectively with the stationary contacts 14 and 15. The stationary contacts are so adjusted that on a decrease in temperature the contact blade 12 will first engage contact 14, and then at a slightly lower temperature the contact blade 13 will engage stationary contact 15.

Indicated generally at 17 is a thermally timed safety switch comprising a bimetallic blade 18 fixed at its lower end and cooperating at its upper end with a pair of resilient contact blades 19 and 20 which are biased open but which are latched in closed position by means of the blade 18 when it is in its cold position as shown in the drawing. Indicated at 21 is an electric heater 30 for heating the thermal blade 18 and causing it to warp as indicated by the arrow in the drawing. After it has been heated for a predetermined period of time, it will move from beneath the switch blade 26 and permit the blades 19 and 20 to move to open circuit position under the influence of their bias. The opening of this safety switch deenergizes the heater 21 thereby cooling the thermal blade 18. The switch cannot be reclosed automatically by the blade but

40 must be reset manually by means of the trip-free reset member indicated at 22. As the member 22 is raised, both blades 19 and 20 are raised and the thermal blade 18 is permitted to return to its cold position. It will be noted that the long leg 45 of the reset member 22 will maintain contact blade 19 out of engagement with the switch blade 20 during the reset operation and this switch can be closed only if the thermal blade 18 is in its cold position and only after the reset member 22 50 has been released, thereby providing for a trip-free action. This switch has been shown more or less diagrammatically and may take any one of several forms. One form which this switch may take is shown in my Patent 2,237,262.

55 Indicated generally at 25 is a conventional

type of two wire, closed cold combustion switch. This switch is shown as comprising a movable switch blade 26 and a stationary contact 27. The blade 26 is intended to be moved by means of a combustion responsive device which may take the form of a thermal element responding either directly to radiant heat of the combustion chamber or it may be mounted in the stack and respond to the temperature of the products of combustion. It is usual practice to interpose a slip friction connection between the thermal element and the blade 26 to provide for the blade being actuated immediately upon a reversal of temperature change so that the operation of the switch will be responsive immediately to the appearance or disappearance of combustion within the furnace and will not be dependent for operation upon the attainment of any predetermined temperature at the thermal element.

A relay winding is indicated at 30 for controlling an armature 31 which in turn actuates a series of switch arms 32, 33, 34, 35 and 36. Switch arm 34 cooperates with an out contact 37 and the switch arms 32, 33, 35 and 36 cooperate with in contacts 38, 39, 40 and 41, respectively.

Relay winding 44 is adapted to control armature 45 which in turn actuates the switch arms 46, 47, 48 and 49. The switch arm 46 cooperates with out contact 50 and the switch arms 47, 48 and 49 cooperate with in contacts 51, 52, 53, respectively.

This system controls the usual oil burner motor 55 which when energized delivers oil to a combustion chamber for establishing combustion therein. The usual ignition device 56 is provided for igniting the oil.

Electrical power for operating the system is supplied from the two line wires 60 and 61. The low voltage portion of the system is fed from the secondary winding 62 of a stepdown transformer indicated at 63, said transformer being provided with the usual primary winding 64 connected across the line wires 60 and 61 by means of conductors 65 and 66.

Operation

The parts are shown in the drawing in the position which they will assume when the room thermostat 10 is satisfied and the two switch blades 12 and 13 are therefore out of engagement with their respective stationary contacts 14 and 15. At this time both of the relay windings 30 and 44 will be deenergized as will be the oil burner motor 55 and the ignition device 56. There will be no combustion present in the furnace and therefore the combustion responsive switch 25 will be in closed position. The safety switch thermal blade 18 will be in its cold position as shown, holding the contact blades 19 and 20 closed.

As a result of the above condition, the temperature in the room will decrease and the thermal element 11 of the room thermostat will cause switch blade 12 to engage stationary contact 14. This will have no effect on the control system due to the fact that the switch arms 32 and 47 are in open circuit position. The room temperature will therefore continue to decrease and eventually the switch blade 13 will engage stationary contact 15. This will establish a circuit from one side of the secondary winding 62 through conductor 70, stationary contact 14, switch blades 12 and 13, stationary contact 15, conductor 71, out contact 50, switch arm 46, conductors 12 and 73, relay winding 30, conductor 74, switch arm

26, contact 27, conductor 75, heater 21, conductors 76 and 77, switch blades 20 and 19, and conductor 78 back to the other side of secondary winding 62. This circuit therefore electrically connects relay winding 30 and electric heater 21 in series across the secondary winding 62 and results in the energization of the relay winding 30 as well as the heater 21.

Upon being energized the relay winding 30 pulls in its armature 31 causing the switch arm 34 to move out of engagement with its stationary contact 37 and causing the contact arms 32, 33, 35 and 36 to move into engagement with their stationary contacts 38, 39, 40 and 41, respectively. The movement of the contact arms 35 and 36 into engagement with their stationary contact establishes a circuit from the line wire 60 through conductors 80 and 81, stationary contact 40, switch arm 35, conductor 82, switch arm 36, stationary contact 41, conductor 83, ignition device 56, and conductors 84 and 85 back to the other line wire 61. This circuit renders the ignition device operative.

The operation of the switch arm 34 from the stationary contact 37 has no effect on the system inasmuch as no circuit was passing therethrough. The engagement of the contact arm 32 with its stationary contact 38 establishes a holding circuit for the relay winding 30 which is independent of switch blade 13 and stationary contact 15. This circuit may be traced from one side of the secondary winding 62 through conductor 70, stationary contact 14, switch blade 12, bimetallic element 11, conductors 87 and 88, stationary contact 38, switch arm 32, conductors 89 and 73, relay winding 30, conductor 74, switch arm 26, contact 21, conductor 75, electric heater 21, conductors 76 and 77, switch blades 20 and 19, and conductor 78 back to the other side of the secondary winding 62. The purpose of this circuit is merely to establish a more reliable circuit for the relay winding 30 in view of the fact that contact between the switch blade 13 and contact 15 is never very firm and this switch is apt to chatter. Inasmuch as the circuit between the switch blade 12 and the contact 14 is made first, this contact will be firm and may be depended upon to hold in the relay 30.

Engagement of the switch arm 33 with its contact 39 results in the energization of relay winding 44. This circuit may be traced from one side of the secondary winding 62 through conductor 70, contact 14, switch blade 12, bimetallic element 11, conductors 87 and 88, contact 38, switch arm 32, conductor 90, switch arm 33, contact 39, conductors 91, 92 and 93, relay winding 44, conductors 94 and 71, switch blades 20 and 19, and conductor 78 back to the other side of the secondary winding 62.

Energization of this relay winding 44 results in the movement of switch arm 46 out of engagement with its stationary contact 50. This breaks the original circuit through which the relay winding 30 was energized, but it will be noted that the holding circuit for the relay winding 30 is independent of switch arm 46 and therefore relay winding 30 remains energized. Movement of switch arm 47 into engagement with its stationary contact 51 sets up a holding circuit for the relay winding 44 which is independent of the switch arms 32 and 33 under the control of relay winding 30. This holding circuit may be traced from one side of the secondary winding 62 through conductor 70, contact 14, switch blade 12, bimetallic element 11, conductors 87 and 90,

switch arm 47, contact 51, conductors 97 and 93, relay winding 44, conductors 94 and 11, switch blades 20 and 19, and conductor 78 back to the other side of the secondary winding 62. It will therefore be seen that at this time the relay winding 44 is held in through the switch blade 12 on the room thermostat 10 and its stationary contact 14 and is independent of the action of the relay winding 30 and the combustion switch 25.

Energization of the relay winding 44 also results in rendering the burner motor 55 operative. The circuit for accomplishing this may be traced from the line wire 60 through conductors 80 and 89, contact 52, switch arm 48, conductor 100, switch arm 49, contact 53, conductor 101, burner motor 55, and conductors 102 and 85 back to the other line wire 62. It will be appreciated that as soon as the relay winding 30 is energized and pulls in its armature 31 that it will energize the relay winding 44 which will immediately pull in its armature 45. Therefore the two armatures 31 and 45 will be pulled in substantially simultaneously which will result in the substantial simultaneous energization of the ignition device 56 and the burner motor 55, although actually the ignition device will be energized a fraction of a second before the burner motor 55.

If combustion is not established as a result of the energization of the ignition device and burner motor, the combustion switch 25 will remain closed and the electric heater 21 will remain energized. After a predetermined time (usually about 90 seconds) the bimetallic blade 18 of the safety switch will warp toward the right far enough to release the switch blades 20 and 19, which will move under their bias to open circuit position. This will result in the deenergization of the two relay windings 30 and 34 which will in turn deenergize the ignition device and burner motor. As set forth above, the safety switch can be returned to closed position only by the manual operation of the reset member 22.

Normally, however, the energization of the ignition device and burner motor will result in the establishment of combustion. In response to combustion, the switch 25 will move to open circuit position which will result in the deenergization of the safety switch heater 21 and relay winding 30 which in turn will deenergize the ignition device 56. This is the running condition of the system. When the room thermostat 10 is satisfied, it will cause the switch blade 12 to separate from contact 14 which will deenergize the relay winding 44 which in turn will deenergize the burner motor 55. The combustion responsive switch 25 will now respond to the absence of combustion in the combustion chamber of the furnace and return to closed position. The parts will now be in the position shown in the drawing and will be ready for another normal start.

Assume now that combustion has been established and the system is in running condition. The combustion switch 25 will be open and the relay winding 30 and ignition device 56 deenergized. It is one of the main objects of the invention to provide a system which will be shut down as rapidly as possible following a flame failure and which will prevent the reenergization of the burner motor and ignition device until after a manual operation has been performed. The present system accomplishes these results because if combustion should fail during a normal run, the combustion responsive switch 25 will first return to closed position. This will

result in connecting the safety switch heater 21 directly across the secondary winding 62 by means of the following circuit: from one side of the secondary 62 through conductor 70, contact 14, switch blade 12, bimetallic element 11, conductors 87 and 96, switch arm 47, contact 51, conductors 97 and 92, switch arm 34, contact 31, conductors 103 and 74, switch blade 26, contact 27, conductor 75, heater 21, conductors 76 and 11, switch blades 20 and 19, and conductor 78 back to the other side of the secondary winding 62. It will be recalled that on an original call for heat the safety switch heater 21 was connected in series with the relay winding 30. Now it will be noted that this heater is connected directly across the secondary winding 62 and therefore it will give off a much greater amount of heat at this time than on an original call for heat with the result that the bimetallic blade 18 will release the safety switch blades 20 and 19 in a much shorter period of time than the ninety second timing interval which must elapse before the system shuts down on an original call for heat. After the switch blades 20 and 19 have moved to open circuit position as a result of their bias, the system will be effectively deenergized and locked out and cannot be reenergized until the safety switch has been reset by the manual member 22. In other words this system will not recycle following a flame failure.

It will therefore be seen that I have provided a system in which the safety switch shuts the system down after a flame failure and prevents recycle wherein the safety switch timing is very much shorter following a flame failure than it is upon an original call for heat.

Various changes and modifications of this system will doubtless occur to those who are skilled in the art, and I therefore wish it to be understood that I do intend to be limited only by the scope of the appended claims and not by the specific embodiment disclosed.

I claim as my invention:

1. A fuel burner control system comprising in combination, a fuel feeding device, a first relay having a first relay winding, a second relay having a second relay winding, a thermally timed safety switch, a heater therefor, a closed cold combustion switch, a main switch, a source of power, a circuit for said first relay winding including said main switch, combustion switch, heater, and source of power, a first switch closed by said first relay, a circuit for said second relay winding including said main switch and first switch, second and third switches closed by said second relay, a circuit for said fuel feeding device including said second switch, a holding circuit for said second relay winding including said main switch and third switch, the opening of said combustion switch upon the establishment of combustion breaking the circuit for said first relay winding, and a circuit established by said combustion switch upon a subsequent failure of combustion, said circuit connecting said heater directly across the source of power and including said main switch, third switch, and combustion switch.

2. A fuel burner control system comprising in combination, a fuel feeding device, a first relay having a first relay winding, a second relay having a second relay winding, a thermally timed safety switch, a heater therefor, a closed cold combustion switch, a main switch, a source of power, first and second "out" switches closed by

said first and second relays respectively when they are deenergized, an energizing circuit for said first relay comprising said main switch, second "out" switch, first relay winding, combustion switch, heater, and source of power, first and second "in" switches closed by said first and second relays respectively when energized, an energizing circuit for said second relay comprising said main switch, first "in" switch, second relay winding, and source of power, a holding circuit for said second relay including said main switch, second "in" switch, second relay winding, and source of power, a third "in" switch closed by said second relay when energized, a circuit for said fuel feeding device including said third "in" switch, said combustion switch opening upon the establishment of combustion to deenergize said first relay, and a circuit established upon a subsequent failure of combustion comprising said main switch, second "in" switch, first "out" switch, combustion switch, heater, and source of power.

3. A fuel burner control system comprising in combination, a fuel feeding device, a first relay having a first relay winding, a second relay having a second relay winding, a thermally timed safety switch, a heater therefor, a closed cold combustion switch, a main switch, a source of power, first and second "out" switches closed by said first and second relays respectively when they are deenergized, an energizing circuit for said first relay comprising said main switch, second "out" switch, first relay winding, combustion switch, heater, and source of power, first and second "in" switches closed by said first and second relays respectively when energized, an energizing circuit for said second relay comprising said main switch, first "in" switch, second relay winding, and source of power, a holding circuit for said second relay including said main switch, second "in" switch, second relay winding, and source of power, a third "in" switch closed by said second relay when energized, a circuit for said fuel feeding device including said third "in" switch, said combustion switch opening upon the establishment of combustion to deenergize said first relay, a circuit established upon a subsequent failure of combustion comprising said main switch, second "in" switch, first "out" switch, combustion switch, heater, and source of power, and an intermittent ignition device for the fuel controlled by said first relay.

4. A fuel burner control system comprising in combination; a fuel feeding device; a relay hav-

ing a relay winding, an "in" switch closed by said relay when it is energized, and an "out" switch closed by said relay when it is deenergized; a thermally timed safety switch, a heater therefor; a closed cold combustion switch; a main switch; a source of power; an energizing circuit for the winding of said relay comprising said main switch, said combustion switch, heater, and said source of power; means controlled by said main switch and said safety switch operative upon closure of said "in" switch to initiate energization of said fuel feeding device and to maintain such energization independently of said "in" switch; and circuit means including said "out" switch and said combustion switch operative upon the reclosure of said combustion switch due to flame failure following the deenergization of said relay as the result of a previous establishment of combustion to cause said heater to be connected substantially directly across said source of power and independently of said relay winding.

5. A fuel burner control system comprising in combination; a fuel feeding device; igniting means; a relay having a relay winding, first and second "in" switches closed by said relay when it is energized, and an "out" switch closed by said relay when it is deenergized; a thermally timed safety switch, a heater therefor; a closed cold combustion switch; a main switch; a source of power; an energizing circuit for the winding of said relay comprising said main switch, said combustion switch, heater, and said source of power; means including one of said "in" switches operative to cause operation of said ignition means during closure of said "in" switch; means controlled by said main switch and said safety switch operative upon closure of the other "in" switch to initiate energization of said fuel feeding device and to maintain such energization independently of said other "in" switch; said combustion switch being operative upon initiation of combustion to open said energizing circuit for said relay and thereby to terminate operation of said ignition means; and circuit means including said "out" switch and said combustion switch operative upon the reclosure of said combustion switch due to flame failure following the deenergization of said relay as the result of a previous establishment of combustion to cause said heater to be connected substantially directly across said source of power and independently of said relay winding.

ERNEST M. MILLER.
